CLAIM

The ornamental design for a seating unit, as shown and described.

DESCRIPTION

FIG. 1 is a top, front, right perspective view of a seating unit embodying our new design;

FIG. 2 is a right side elevational view thereof, the left side elevational view thereof being a mirror image of the right side shown;

FIG. 3 is a top plan view thereof;

FIG. 4 is an exploded bottom, front, right perspective assembly view of seat and base components thereof;

FIG. 5 is an enlarged bottom, front perspective view of the seat component thereof; shown separately for completeness of disclosure;

FIG. 6 is an enlarged top, front, right perspective view of the base component thereof; shown separately for completeness of disclosure;

FIG. 7 is an enlarged exploded top, front, right perspective assembly view of the sub-components of the base component thereof; shown separately for ease of illustration;

FIG. 8 is an enlarged top plan view of the base component thereof; and,

FIG. 9 is an enlarged bottom plan view of the base component thereof.

The broken line representations in FIGS. 4 and 7 are assembly lines, and thus form no part of the claimed design.
